BEGINNER'S HARP

Walter Krasicki, 5810 W. Schubert,
Chicago, Ill. 60639

Filed Dec. 27, 1972, Ser. No. 319,027

Term of patent 14 years

Int. Cl. D17—03

U.S. Cl. D56—1 A

FIG. 1

FIG. 2

FIG. 3

FIG. 4

FIG. 5

FIG. 6

FIG. 7

FIG. 8

FIG. 1 is a right side elevational view of a beginner's harp showing my new design;

FIG. 2 is a front elevational view;

FIG. 3 is a rear elevational view;

FIG. 4 is a top plan view;

FIG. 5 is a sectional view taken along line 5—5 of FIG. 1 and on an enlarged scale;

FIG. 6 is a sectional view taken along line 6—6 of FIG. 1 and on an enlarged scale;

FIG. 7 is a portional view of the sound board of the harp; and

FIG. 8 is a left side elevational view.

I claim:
The ornamental design for a beginner's harp, as shown.
